UNITED STATES PATENT OFFICE.

GEORGE W. WALKER, OF TAMA, IOWA.

GRATE-BAR AND SHAKER ATTACHMENT FOR FURNACES.

SPECIFICATION forming part of Letters Patent No. 476,584, dated June 7, 1892.

Application filed July 31, 1891. Serial No. 401,266. (No model.)

To all whom it may concern:

Be it known that I, GEORGE W. WALKER, a citizen of the United States of America, residing at Tama, in the county of Tama and 5 State of Iowa, have invented certain new and useful Improvements in Grate-Bars and Shaker Attachments for Furnaces, of which the following is a specification, reference being had therein to the accompanying drawings.

My invention relates to certain improvements in fire-grates for furnaces, &c.; and it consists of the detailed construction and combination of parts as hereinafter set forth, and 15 pointed out in the claims.

Figure 1 is a plan view of my improved grate-bar and shaker attachment for furnaces. Fig. 2 is a longitudinal section of one of the grate-bars. Fig. 3 is a cross-section on the 20 line $x-x$ of Fig. 1. Fig. 4 is a front view of the invention. Fig. 5 is a detailed sectional view taken on a straight line through the parts B d b^2 g. Fig. 6 is a cross-section taken on the line $z-z$ of Fig. 1, and Fig. 7 is a longitudinal section taken on the line Y Y of 25 Fig. 1.

In the accompanying drawings, A A represent the series of grate-bars having their rear ends provided with circular or disk-like enlargements a, themselves provided in their 30 upper surfaces with recesses, the longitudinal portions of said bars having their upper surfaces provided with grooves, these enlargements permitting the bars to stand the requisite intervals apart. These bars taper toward their forward ends and have their disk-like or circular rear ends provided with pendant pivot-pins or pintles b, engaging coincident sockets b' in the upper end of the rear 35 cross-piece c in the stove or furnace base, thus pivoting or hinging said bars at said ends.

The forward or tapering ends of the bars A rest on the front cross piece or bar d in the stove or furnace base and are adapted for en-

gagement with the teeth of the notched or 45 toothed sliding bar B, resting upon the bar d and having its ends guided in apertures in side plates of said stoves or furnace base, while depending from the forward edge of the sliding bar B is a flange b^2 , extending forward 50 between and limited in its movement by stops or projections e on the forward edge of the bar d. The flange b^2 has an aperture f, adapted to receive the bar or lever g' for actuating the slide or bar B, which in turn shakes or vibrates the grate-bars. This aperture also 55 registers or coincides with a corresponding aperture f' in a pendent lug or projection g on the inner edge of the bar d, adapted to receive the inner end of the bar or lever g' to 60 provide for holding the slide or bar B stationary and accordingly prevent the accidental movement by the weight or pressure of the contents of the combustion-chamber of the grate-bars.

Having thus fully described my invention, I claim—

1. The fire-grate having the sliding notched or toothed bar, the pivoted or hinged bars whose free ends rest within the notches of said 70 sliding bar, and means for actuating said sliding bar, substantially as set forth.

2. The combination, in a fire-grate, of the pivoted or hinged bars and the toothed or notched sliding bar having at its forward edge 75 a flange provided with a lever-receiving aperture registering with a corresponding aperture in a lug depending from the front support of said pivoted or hinged bars, said latter bars having their free ends resting within 80 the notches of said toothed or notched bar, substantially as set forth.

In testimony whereof I affix my signature in presence of two witnesses.

GEORGE W. WALKER.

Witnesses:

A. W. GUERNSEY,
W. A. SHARPE.
